UNITED STATES PATENT OFFICE

WILLIAM D. FERRIS, OF STERLING, ILLINOIS, ASSIGNOR TO FRANTZ MANUFACTURING CO., OF STERLING, ILLINOIS, A CORPORATION OF ILLINOIS

GARAGE-DOOR CONSTRUCTION

Application filed April 27, 1928. Serial No. 273,168.

This invention relates to garage doors, and more particularly to doors of this kind comprising sliding sections that are hinged together and provided with hangers that travel on an overhead track, and having a swinging door section hinged to one of the sliding door sections.

Generally stated, the object of the invention is to provide a novel and improved construction and arrangement whereby the said swinging door section is also supported, in opening and closing the door structure, preventing the swinging door section from swinging around during the sliding movement, but permitting the swinging door section to swing inward without disturbing the sliding section to which it is hinged.

It is also an object to provide certain details and features of construction and combinations tending to increase the general efficiency and the desirability of a sliding garage-door structure of this particular character.

To the foregoing and other useful ends, the invention consists in the matters hereinafter set forth and claimed and shown in the accompanying drawings, in which,—

Fig. 1 is a plan view of a garage-door construction involving the principles of the invention, showing the wall of the building in horizontal section.

Fig. 2 is an enlarged detail vertical sectional view showing the connection of the swinging door and one of the hangers, showing the parts in one position.

Fig. 3 is a similar view, showing the parts in different positions.

Fig. 4 is a front elevation of the said garage-door construction, looking at the same from inside the building.

Fig. 5 is a fragment of the structure shown in Fig. 4, showing the swinging door partially open.

Fig. 6 is an enlarged detail plan view of an extensible link connection between the spe-

cial hanger for the swinging door section, and one of the hangers for the sliding door sections.

Fig. 7 is an enlarged front elevation of the special hanger for the swinging door section.

Fig. 8 is a detail horizontal sectional view, showing a different form of the invention.

Fig. 9 is a detail fragmentary view, showing another form of the invention.

Fig. 10 is an enlarged front elevation of the special hanger shown in Fig. 9, with a portion thereof in vertical section.

Fig. 11 is a front elevation of the construction shown in Fig. 8.

Fig. 12 is a detail view showing another form of the invention.

As thus illustrated, and referring to Figs. 1 to 7, inclusive, it will be seen that the door structure comprises the sliding door sections 1 and 2 hinged together by the hinges 3, and a swinging door section 4 hinged to the section 2 by the hinges 5, as shown. The upper hinges 3 and 5 have door hangers 6 and 7 that travel within and on the overhead track and housing 8, which latter, as shown in Fig. 1, extends above the doorway and has a curved bend 9 that connects it with the track or housing 10 on the side wall of the building, it being understood that this track and housing

can be of any suitable known or approved construction. In other words, the track has a straight section disposed over the doorway, a straight section disposed in the same plane on the side wall of the building, and a curved section connecting the two straight sections. With this construction, the hangers 6 and 7, and the similar hanger 11 for the door section 1, may travel freely along the straight section 8 and then along the curved section 9, and then along the straight section 10, when it is desired to open the door structure in the well known manner.

The swinging door section 4 is ordinarily provided with a lock (not shown) for lock-

75

80

85

90

95

ing it in closed position. When unlocked, this swinging door section 4 can be opened to permit entrance to the garage or building, and the entire door structure can then be moved around, as stated, until the entire doorway is open, it being understood that the section 10 is of sufficient length for this purpose.

As shown in Figs. 1 to 7, inclusive, the special hanger 12 is provided to travel within 10 and upon said housing and track, this hanger having a lower portion 13 connected by an adjustable or extensible link 14 with the swivel rod 15 of the hanger 7, as shown. By means of the bolts 16 and the slots 17 in this link, its length can be varied to suit the requirements of different cases. It will be seen that one end of the link is pivoted by a pivot 18 on one end of the portion 13 previously mentioned. The door section 4 is provided 20 with a latch bolt 19, as shown more clearly in Figs. 2 and 3, having its upper end formed to engage and disengage the lower portion 13 of the special hanger. This latch bolt has a coiled spring 20 to keep it normally in raised position, and the lower end of the bolt has a chain or pull cord, or other connection 21, by which the bolt may be pulled down.

Assuming that the door structure is in closed position, the mode of operation is as 30 follows:

The swinging door section 4 will be unlocked, and will be pushed inwardly to cause the upper end portion of the bolt 19 to be depressed and pass below the portion 13, as 35 shown in dotted lines in Fig. 3 of the drawings. Thereafter, when the bolt 19 has passed out from under the portion 13, and is then in raised position, shown in full lines in Fig. 3, the door section 4 will then be pulled outward 40 until the bolt 19 is in engagement with the portion 13, as shown in Fig. 2 of the drawings. In this position, the latch bolt 19 forms a frictional connection between the door section 4 and the special hanger 12, and in this condition 45 all three door sections are supported on the track, and the whole structure can then be moved in the direction necessary to fully open the doorway of the garage or building. This is done without the door section 4 being 50 free to flap or swing around in a manner that might interfere with the free and easy opening of the door structure. Thereafter, when it is desired to again close the door structure, the three sections are moved around into position 55 to close the doorway, as shown in Fig. 1 of the drawings, the section 4 is then pulled inwardly until the bolt 19 has disengaged the portion 13, and the pull chain or cord 21 is then pulled downward to depress the bolt 19 into position to pass under the portion 13, and with the bolt in this depressed position the door section 4 is then swung outward into 60 closed position, and the swinging section is then locked, thus locking the entire door 65 structure in closed position.

As shown in Figs. 8 and 11, the swinging door section 4 is not provided with a special hanger, but is provided with a caster 22, and the floor of the building is provided with a curved channel track 23 to receive this caster. Thus the entire door structure can be opened in the manner described, but in this case the swinging door section 4 is controlled by the floor track 23, in which the caster 22 travels, thus guiding the section 4 and preventing it from flapping or swinging around. It will be understood that the track 23 is directly below the overhead track, in this form of the invention, practically, so that the door sections will all have exactly the same path of travel in the operation of opening and closing the door structure.

As shown in Figs. 9 and 10, the swinging door section 4 has a special hanger 24, but this hanger is not connected to any of the other hangers. Instead, this hanger 24 is simply provided with friction portions 25 that engage the bottom of the overhead track, and thus frictionally hold this hanger in any position where it is left, after it is disengaged from the swinging door section. The special hanger 24 has a lower portion 26 for engagement with the latch bolt 27, which latter is similar to the one previously described, and the operation here is substantially the same as that described in connection with Figs. 1 to 7 of the drawings. But, as stated, the hanger 24 is not connected to the next hanger in any way, but depends upon the friction devices 25 to hold it in position to engage the latch bolt 27, in the opening and closing of the door structure.

It will be seen, therefore, that in each form of the invention, means are provided for controlling the swinging door section and for preventing it from flapping or swinging around when the door sections are moved out of the doorway and around to the side of the building. In other words, the swinging door section is not allowed to swing freely back and forth, but, to the contrary, is supported and controlled to travel around in the same path of travel as the other door sections, and the swinging door section only has a capacity for swinging movement inwardly, and only at a time when the sliding door sections are in closed position. As soon as the sliding door sections are out of closed position, to any extent whatever, the swinging door section is then no longer free to swing, but is at such time practically a sliding door section. In each form of the invention, therefore, there is a special wheeled support for the free side of the swinging door section, and a track section for engagement with said wheeled support. When the swinging door is under the control of its special wheeled support, in each form of the invention, it is then operative to slide and move in effect like a sliding section. In each form of the invention, the

swinging door section is free to swing inwardly, after being unlocked, only when the sliding section to which it is hinged is in fully closed position.

5 With further respect to Figs. 9 and 10, it will be understood that the track and housing 8 can be so formed that the friction means 25 will only function at a certain point in the path of travel of the hanger, 10 namely at the point where it is left when the door is disengaged from the hanger, whereby the hanger will slide freely along all other portions of the track and housing.

In Fig. 12 of the drawings, the latch 28 is 15 pivoted at 29 on the locking bolt 19, in a slot 30 in said bolt. The pull cord or chain 21 is attached to the latch 28, as shown, and initial downward pull will disengage this latch from the hanger body 13, so that the 20 door can be disengaged from the hanger, and a further downward pull will then pull the bolt 19 downward far enough to enable it to pass under the hanger body.

Without disclaiming anything, and without prejudice to any novelty disclosed, what 25 I claim as my invention is:

1. In sliding door construction for a garage or other building, the combination of one or more sliding door sections, an inwardly swinging door section hinged to one side edge of a sliding door section to swing free of control when the sliding door structure is in closed position, an overhead track section above the doorway, an overhead track section on the side wall of the building, 35 a curved track section connecting the said two tracks together, traveling means to support the door structure on said track sections, so that the entire door structure can be moved out of the doorway and around the curve and into a position at the side of the building, and guiding instrumentalities serving to prevent any swinging movement of this door section during the sliding movement of the door structure on said side wall 40 track, said instrumentalities having engagement with the swinging door at a point thereon a distance from the hinge support thereof, holding the swinging door section to its course.

50 2. A structure as specified in claim 1, said instrumentalities including means whereby the swinging door section has connection with and disconnection from a track section, whereby the swinging door section is supported and guided in effect like a sliding section.

3. A structure as specified in claim 1, 55 said instrumentalities comprising a special wheeled support having means for supporting the side of the swinging door that swings open to permit entrance into the building, said wheeled support engaging a track section to prevent the swinging door section from flapping or swinging around in the op-

eration of sliding the sectional door structure into open position.

4. A structure as specified in claim 1, said instrumentalities having means normally disconnected from but operative to connect with and control the swinging door section throughout the entire movement necessary to fully open the sectional door structure. 70

5. In door construction, the combination of one or more sliding door sections, a swinging door section hinged thereto, adapted to swing inward, free of control, while the sliding section remains stationary in closed position, forming the leading section when the doors slide open, and instrumentalities having means operative to control and prevent the swinging door section from flapping or swinging around during the sliding movement necessary to fully open the sectional door structure, said instrumentalities having engagement with the swinging door at a point thereon a distance from the hinge support thereof, holding the swinging door section to its course. 75

6. A structure as specified in claim 5, 80 said instrumentalities comprising a special wheeled support having means for supporting the free side of the swinging door section, together with a track section to engage said wheeled support. 85

7. A structure as specified in claim 5, comprising a track, said sliding door section having a hanger supported on said track, and said instrumentalities comprising a hanger having means for supporting said 90 swinging door section on the same track. 100

8. A structure as specified in claim 5, comprising a curved track, and said instrumentalities comprising a wheeled swinging door section support mounted to travel on said track in advance of the hinge support of the swinging door section, when the door structure is opened, whereby the front edge of 105 said swinging door section is held to its course.

9. A structure as specified in claim 5, said swinging door section and instrumentalities leading when the doors slide open. 110

10. In door construction, a swinging door, an overhead vertically reciprocating bolt on 115 said door, having means limiting the upward movement thereof on the door, an overhead support, means on said bolt resting on said support, when the door is in one position and the bolt is in its extreme upward position, thereby supporting the door in said position, and means to reciprocate said bolt. 120

11. A structure as specified in claim 10, comprising a pivoted catch on said bolt engaging said support and disengageable 125 therefrom by said bolt operating means.

12. In door construction, a swinging door, an overhead bolt on said door, a support, means on said bolt resting on said support, thereby supporting the door, and means to 130

operate said bolt, with a pivoted catch on said bolt engaging said support and disengageable therefrom by said bolt operating means.

5 13. A structure as specified in claim 12, said bolt being movable downward into position to pass under said support when said door is moved.

10 Specification signed this 14th day of April, 1928.
